[57] **CLAIM**

The ornamental design for a building block, as shown and described.

DESCRIPTION

FIG. 1 is a front perspective view of one embodiment of the building block;

FIG. 2 is a left side elevational view thereof;

FIG. 3 is a top plan view thereof;

FIG. 4 is a front perspective view of another embodiment of the building block;

FIG. 5 is a rear perspective view of the building block of FIG. 4;

FIG. 6 is a left side elevational view of the building block of FIG. 4;

FIG. 7 is a top plan view of the building block of FIG. 4;

FIG. 8 is a front perspective view of another embodiment of the building block;

FIG. 9 is a left side elevational view of the building block of FIG. 8;

FIG. 10 is a top plan view of the building block of FIG. 8;

FIG. 11 is a front perspective view of another embodiment of the building block;

FIG. 12 is a left side elevational view of the building block of FIG. 11; and

FIG. 13 is a top plan view of the building block of FIG. 11.
